U.S. Cl. D34—5 SS

FIG. 1

FIG. 2

FIG. 3

FIG. 4

FIG. 1 is a plan view of the gameboard showing my new design.

FIG. 2 is a plan view of the gameboard, showing an alternate embodiment of my new design.

FIG. 3 is a plan view of the gameboard, showing another alternate embodiment of my new design.

FIG. 4 is a plan view of the gameboard showing another alternate embodiment wherein the common pattern is vertically disposed on the board.

The gameboard is of conventional thickness, and shaded to illustrate contrasting colors.

The essential feature of the various embodiments of the design is the double-X pattern formed by the contrasting colored circles.

We claim:

The ornamental design for a gameboard, as shown and described.
